UNITED STATES PATENT OFFICE.

ADIEL YEAMAN DODGE, OF CHICAGO, ILLINOIS.

AUTOMATIC TRAIN-STOP.

1,252,330.

Specification of Letters Patent. Patented Jan. 1, 1918.

Application filed January 28, 1914. Serial No. 815,009.

To all whom it may concern:

Be it known that I, ADIEL YEAMAN DODGE, a citizen of the United States, residing at Chicago, in the county of Cook and State of Illinois, have invented new and useful Improvements in Automatic Train-Stop, of which the following is a full, clear, concise, and exact description, reference being had to the accompanying drawing, forming a part of this specification.

My invention relates to improvements in automatic train stops.

Among the principal objects of my invention are:

First: To provide an automatic train stop capable of causing the brakes to be applied gradually, and such that it may be used also in connection with throttle closing apparatus.

Second: To provide such a stop that is self closing after the brakes have been set, independently of the engineer.

Third: To provide such a stop adapted for use with practically any cab signaling system, but particularly adapted to the system set forth in my co-pending application Serial No. 815,010 filed Jan. 28, 1914.

Fourth: To provide a stop such that it allows the train line air to escape at a desired rate until a desired pressure is reached and then retains it, and such that during the time such air is escaping the main reservoir air is confined.

These and other objects will be apparent from the following description and the accompanying drawing, taken in connection with the appended claims.

The drawing is a sectional elevation of an automatic stop constructed in accordance with my invention.

Like reference characters refer to like parts throughout the following description and the drawing.

Referring to the drawing, the stop consists of a double valve comprising two sliding members working in opposition to each other. Each is impelled by the air it confines. I have shown these valves in the form of pistons 13, 14 housed in cylinders 5, 12 but they may be of some other shape. The cylinder 5 and the casing 10 are in one piece. A cap 11 is provided with means to hold the cylinder 12 directly opposite to cylinder 5. Pistons 13, 14 are connected

together by a connecting rod 6 and move as one. Within the casing 10 are two electro-magnets which are yoked together and held in place by any suitable means such as bolts and nuts. Magnets 15 hold armature 8 against their cores when energized. Armature 8 is rigidly connected to the lower part of a special cam 7 which is also located in casing 10 and pivoted in the same at 9. This special cam is a combined lever and cam, and is shaped to straddle the connecting rod 6 and is slotted on both sides to operate on pivot 16 in connecting rod 6. The lower portion of one side of the cam is shown cut and broken away, in order to show the half which remains. The mechanical advantage of this cam is derived from two sources; first, from the lever ratio from the point 9 to the point 16 and from the point 16 to the center of the magnets 15; second, by the angle of the shoulder 26. The fact that this shoulder 26 inclines downwardly and toward the piston 13 makes it necessary for the cam to rock farther for a given travel of the valve than if the shoulder were perpendicular to the line of travel of the valve. When the cam operates it strikes the ratchet lever of a registering apparatus 17 in order to count the operations. This cam might be replaced by a catch and trigger similar to the one illustrated in my co-pending application, Serial No. 768,058 filed May 16, 1913.

The heads of the cylinders are provided with threaded ports 27, 28 which may be connected directly with the desired pipe or with some intermediate member such as I have shown. Port 27 in the head of cylinder 5 is connected with the train line through an adjustable needle valve 18. The port in the head of cylinder 12 is connected to a safety valve 21 or a reduction valve as desired or a combination of both connecting the cylinder with the main reservoir. Cylinder 12 is also provided with a port 20 leading to the engineer's valve and train line located to be opened and closed by the piston 14. Cylinder 5 is provided with additional ports 22 which are exhaust ports. In order that the cylinder 5 should be inaccessible through the exhaust ports they are made in the form of by-passes which conduct the air to the casing 10 and then into the atmosphere through ports 23. If it is desired to utilize the exhaust air to

close the throttle, ports 22 are omitted and a port 19 is provided to exhaust the air into throttle closing apparatus such, for example, as is shown in my co-pending application, Serial No. 768,058, filed May 16, 1913.

In operation air from the train line is admitted to cylinder 5 through port 27 and needle valve 18 which is open according to 10 its adjustment. The constant pressure on piston 13 tends to force it outwardly. Air from the main reservoir enters safety valve 21 at port 25 and is admitted into cylinder 12 through port 28. This constant pressure 15 tends to force piston 14 in opposition to piston 13. The resultant of these two forces is in the direction of the forces on piston 13. The magnitude of this resultant depends on the ratio of the diameter of the 20 two pistons 13 and 14 and the ratio of the two air pressures which act on them. If a reduction valve is used in place of the safety valve 21 this resultant can be adjusted by 25 adjusting the reduction valve to control the air pressure admitted to cylinder 12. Whereas without the reduction valve the resultant force can only be regulated by the ratio of the piston area. To hold the piston 13 in normal confining position the cam 30 7 bears against the pivot 16, the cam being held in place by the engagement of the armature 8 with the electromagnets 15. While in this normal position, air from the main reservoir enters cylinder 12 and is 35 conducted to the engineer's valve through port 20. When magnet 15 becomes energized armature 8 and cam 7 are released and piston 13 moves outward forcing piston 14 inward. As the head of piston 13 uncovers the ports 22 the air begins 40 to escape from the train line through needle valve 18, cylinder 5, ports 22 and 23, into the atmosphere thereby stopping the train. During this operation the cam strikes the 45 ratchet lever of the counting device 17 and causes it to register an operation of the stop. Piston 14 now covers port 20 shutting off air between the reservoir and the rest of the air brake equipment.

50 When the air in the train line has reached the predetermined pressure the force of piston 14 over-balances the force of piston 13 causing it to recede until communication is closed between train pipe 24 and ports 22. The two pistons reach a fluctuant equilibrium at this point. The port 20 is covered prior to the uncovering of 55 ports 22 in order to prevent air from passing from the main reservoir into the train line while the pistons are in operation. In order to cause piston 13 to return to its normal position the engineer must further reduce the air pressure in the train line by opening his brake valve, when piston 14 60 will force piston 13 back and will rock cam

7 so that armature 8 will come in contact with the cores of magnets 15. If the magnets are energized they will hold the armature 8 and cam 7 will again retain piston 13 in its normal position.

It will be noted that the cam 7 is continuously in contact with the pivot 16, thus facilitating the automatic return of the cam to retaining position. It will be further seen that I have provided a stop simple in 75 its nature, for inasmuch as the pistons are connected with one another and the cam and armature are connected, there are but two moving parts.

It will be apparent that numerous 80 changes may be made in the form, arrangement and construction of the parts without departing from the spirit of the invention or exceeding the scope of the appended 85 claims, the form of my invention herein described being merely one preferred embodiment thereof.

Having thus described my invention, what I claim as new and desire to secure by Letters Patent, is:

1. An automatic train stop comprising a member arranged to confine the train line air under normal conditions, means for normally retaining said member in such confining position, said retaining means being automatically releasable, said member being so arranged that when released it will be impelled in one direction by the force of the train line air and back to normal position by the force of the main reservoir air, and 95 means for permitting said train line air to escape when said member is out of said normal position, thereby to stop the train.

2. An automatic train stop comprising a member arranged to confine the train line 105 air under normal conditions, means for normally retaining said member in such confining position, said retaining means being automatically releasable, said member being so arranged that when released it will be 110 impelled in one direction by the force of the train line air and back to normal position by the force of the main reservoir air, and means for permitting said train line air to escape gradually when said member is out 115 of said normal position, thereby to stop the train.

3. An automatic train stop comprising a member arranged to confine the train line 120 air under normal conditions, means for normally retaining said member in such confining position, said retaining means being automatically releasable, said member being so arranged that when released it will be 125 impelled in one direction by the force of the train line air and back to normal position by the force of the main reservoir air, and means for permitting said train line air to escape when said member is out of said normal position, said retaining means being 130

tomatically returned to said normal retaining position after the engineer's valve is opened.

4. An automatic train stop comprising a member arranged, under normal conditions, to confine the train line air, means for normally retaining said member in such confining position, said retaining means being automatically releasable, said member being so arranged as to be moved by the force of the train line air when said retaining member is released, into such position that the train line air escapes, and a member associated with said first named member and impelled by the force of the main reservoir air to return said first named member to normal position.

5. An automatic train stop comprising a member arranged, under normal conditions, to confine the train line air, means for normally retaining said member in such confining position, said retaining means being automatically releasable, means for allowing said train line air to escape thereby to stop the train when said member is released, and a member associated with said first named member and arranged to confine the main reservoir air while said train line air is being permitted to escape as aforesaid.

30 6. An automatic train stop comprising a member arranged, under normal conditions, to confine the train line air, means for normally retaining said member in such confining position, said retaining means being automatically releasable, an adjustable port for allowing said train line air to escape thereby to stop the train when said member is released, and a member associated with said first named member and arranged to 35 confine the main reservoir air while said train line air is being permitted to escape as aforesaid.

7. An automatic train stop comprising a double valve, one portion of which is arranged to confine the train line air under normal conditions, means for normally retaining said valve in such position, said means being automatically releasable, and means for causing said valve to move when released into such position, that said train line air is permitted to escape, the other portion of said valve being arranged to confine the main reservoir air when said valve is in said last named position.

55 8. An automatic train stop comprising a reciprocating member arranged, under normal conditions, to confine the train line air when in one position and to confine the reservoir air when in another position, means for normally retaining said member in said first-named position, means for releasing said retaining member, thereby to allow said member to move into a position to permit the escape of said train line air, and means 60 for returning said member to normal position.

tion, said retaining means being continuously in contact with said member.

9. An automatic train stop comprising a reciprocating member arranged, under normal conditions, to confine the train line air when in one position and to confine the reservoir air when in another position, means for normally retaining said member in said first named position, electromagnetic means for releasing said retaining member, thereby to allow said member to move into a position to permit the escape of said train line air, and means for returning said member to normal position, said retaining means being continuously in contact with said member. 75 80

10. An automatic train stop comprising a reciprocating member arranged, under normal conditions, to confine the train line air when in one position and to confine the reservoir air when in another position, a cam arranged to normally retain said member in said first named position, means for releasing said cam, thereby to allow said member to move into a position to permit the escape of said train line air, and means for returning said member to normal position, said cam being continuously in contact with said member. 85 90

11. An automatic train stop comprising a reciprocating member arranged, under normal conditions, to confine the train line air when in one position and to confine the reservoir air when in another position, a cam arranged to normally retain said member in said first named position, electromagnetic 100 means for releasing said cam, thereby to allow said member to move into a position to permit the escape of said train line air, and means for returning said member to normal position, said cam being continuously in contact with said member. 105

12. The combination with an automatic train stop for railroad signaling systems, arranged to apply the brakes gradually and to confine the reservoir air during such operation, of means for releasing the brakes by first opening the engineer's valve to further reduce the air pressure to a predetermined extent. 110

13. An automatic train stop comprising a pressure-chamber in communication with the train line, a pressure-actuated member actuated by the pressure in said chamber, means whereby actuation of said member releases the air in said train pipe, a second pressure-chamber in communication with the reservoir, a second pressure-actuated member actuated by the pressure in said second chamber, and means whereby the actuation of said second pressure-actuated member confines the air in the train pipe. 115 120 125

14. An automatic train stop comprising a pressure-chamber in communication with the train line, a pressure-actuated member actuated by the pressure in said chamber, means 130

- whereby actuation of said member releases the air in said train pipe, a second pressure-chamber in communication with the reservoir, a second pressure-actuated member actuated by the pressure in said second chamber, and means whereby the actuation of said second pressure-actuated member confines the air in the train pipe and returns said first pressure-actuated member.
- 10 15. An automatic train stop comprising a pressure-chamber in communication with the train line, a pressure-actuated member actuated by the pressure in said chamber, means whereby actuation of said member releases the air in said train pipe, a second pressure-chamber in communication with the reservoir, a second pressure-actuated member actuated by the pressure in said second chamber, and means whereby the actuation of said second pressure-actuated member confines the air in the train pipe and returns said first pressure-actuated member, and automatically-controlled means for normally holding said pressure-actuated members in position to confine the train pipe air.
16. An automatic train stop comprising a pressure cylinder in communication with the train line, a piston in said cylinder actuated by the pressure therein, means whereby ac-
- tuation of said piston releases the air in said train pipe, a second pressure cylinder in communication with the reservoir, a second piston actuated by the pressure in said second cylinder, and means whereby the actuation of said second piston confines the air in the train pipe.
17. An automatic train stop comprising a pressure-chamber in communication with the train line, a pressure-actuated member actuated by the pressure in said chamber, a second pressure chamber in communication with the reservoir, a second pressure-actuated member actuated by the pressure in said second chamber, and means whereby actuation of said first pressure-actuated member releases the air in said train pipe, and whereby actuation of said second pressure-actuated member confines the air in the train pipe and returns said first pressure-actuated member.

In witness whereof, I have hereunto subscribed my name in the presence of two witnesses.

ADIEL YEAMAN DODGE.
